United States Patent Office.

WILLIAM BAHME, OF NEW MEDIA, PENNSYLVANIA.

Letters Patent No. 72,587, dated December 24, 1867.

IMPROVEMENT IN MILLSTONES.

The Schedule referred to in these Letters Patent and making part of the same.

TO ALL WHOM IT MAY CONCERN:

Be it known that I, WILLIAM BAHME, of New Media, in the county of Columbia, and State of Pennsylvania, have invented a new and useful Device for Sinking the Bosoms of Millstones; and I do hereby declare the following to be a full, clear, and exact description of the same, reference being had to the accompanying drawing, which is made part of this specification.

After repeated dressings, that part of the face nearest the skirt is worn down until the bosom of the stone becomes prominent, and it is necessary to sink it, to perform which labor with dispatch and ease is the object of my invention, which consists in the use of a stone of proper circumference to suit the size of the run of stones, having its grinding-face convex or bevelled, and suitably roughened to cut the stone to be acted on, which, by being placed in the centre of the face of the stone, and motion imparted to it, quickly and accurately performs the work. In the drawings—

Figure 1 is a plan view of a run of stones, showing one mode of applying my invention, the runner being turned up, as for dressing.

Figure 2 is an elevation with partial vertical section on the line $z z$, fig. 1.

Figure 3 is a vertical section of a different mode of applying my invention, showing the runner turned up on the bed-stone, and motion imparted to the bosom-sinking stone from the ordinary spindle.

A A' represent, respectively, the bed-stone and runner of a run of stones. B is the main driving-shaft, from suitable gearing or pulleys on the lower end of which the spindle C is operated. This shaft, at any suitable height, is provided with a pulley, D, which I prefer to construct with a flange, d, by which, through the belt E, motion is imparted to the pulley F, constructed similarly to the pulley D, on the shaft G, the upper end of which is journalled in a suitable bearing directly over the centre of the "runner," (when turned over,) and its lower end has its seat or step in the cock-eye in the cross-bar α , the driver being removed to allow its attachment. The shaft G, at a proper point, is made square, as shown at g , which part fits the opening in the driver h of the stone H, in coffins, in the lower side of which the driver is secured in the usual way. The lower side of stone H is convex or bevelled, and is provided with radial furrows, which act on and wear away that part of the stone which they come in contact with. When the stone H is to be used on the bed-stone A, it is placed thereon, as shown in red lines, being driven by the ordinary spindle C, over which its driver h fits in the customary manner. When the rynd may be readily removed the runner may be simply turned up on the bed-stone A, as shown in fig. 3; and the rynd and driver being removed, the stone H is applied and motion imparted to it from the ordinary spindle C, through an upright shaft, I. This shaft is constructed with a square tubular opening, i , in its lower end, which fits the upper end of the spindle, and a square, i' , at a proper distance above, to engage with the driver h , and at its upper end is secured in suitable bearings in the ceiling or rafters. When not in use, the shafting, with their appendages, may be removed and stowed away in any suitable place.

Having thus described my invention, what I claim as new, and desire to secure by Letters Patent, is—

1. The stone H, adapted and employed to sink or grind out the central portion of millstones, substantially as and for the purposes set forth.
2. The shaft G g and driving-apparatus D E F, in the described combination with the stone H, for the purpose specified.
3. The upright shaft I, constructed as described, in combination with the spindle C and stone H, substantially as and for the purpose specified.

WILLIAM BAHME.
